Pierre A. Berthold and Macklet Thompson, of St. Louis, Mo.

Letter Patent No. 2,805 Dated, May 6, 1866

Design for a Trade Mark.

The substance referred to in these letters patent and making part of the same
is as follows it may concern:

Best known that we, Pierre A. Berthold and
Macklet Thompson, both of St. Louis, in the County of St. Louis and State of
Missouri, have originated and devised a new design for a Trade Mark, of
which the following is a full, clear and exact description, reference being
had to the accompanying drawing.

As seen in the drawing the design consists of two keys
placed that their loops will form the top of the design. About one
way between their two ends the shanks of the keys cross one another at such
an inclination, that the angle formed between their lower ends may be
about 135° . The bit or ends of the keys are turned outwards
so as to be as far removed from each other as possible. Upon the face
of the bit of the left hand key is cut or formed the letter or initial R
and upon the face of the bit of the right hand key is formed in like
manner the letter or initial T. The bit upon which is marked the
letter R is divided into two portions, viz: a small, which runs perpendicular
early to the shank of the key and the initial R is placed thereon, and
half, which is on the upper portion of the bit, and its lower portion
carrying lower portion of the bit. The letter or initial T is
also to be run in like manner in relation to its bit.

Des. 2305

2

Having thus described the device originated by us in but
not claim and desire to secure by Letters Patent
the design for a trade-mark as hereinabove and as aforesaid.
In testimony whereof we have signed our names to this application, in the
presence of two subscribing witnesses:
